ADJUSTABLE CURTAIN

Hugo Geller, New York, N. Y., assignor to
 Patchogue-Plymouth Mills Corporation, New
 York, N. Y., a corporation of New York

Application January 12, 1935, Serial No. 1,449

5 Claims. (Cl. 156—10)

This invention relates to improvements in adjustable curtains such as are disclosed generally in my issued Patent # 1,971,712, granted August 28, 1934, and the present application is a continuation in part of my former application, Serial Number 741,614, filed August 27, 1934.

One object of this invention is a ready-to-hang adjustable curtain which may be locked to the curtain rod in any selected position.

10 Another object is a ready-to-hang curtain which may be adjustably suspended upon the curtain rod at any desired length, adjusted upon the rod to any preferred width and degree of ornamentation, and thereafter locked to the rod at the selected width to fix and retain the selected ornamental effect.

Other objects will appear from the detailed description which follows:

According to this invention, the curtain is made 20 appreciably longer than the corresponding conventional curtain formerly used for any given size window, so that the curtain top constitutes in effect an extension of the corresponding conventional curtain throughout its width; and a

25 plurality of horizontal rod engaging passageways including rows of eyelets are fashioned in the said curtain top or extension, said passageways which are large enough to allow the free passage of a conventional curtain rod may be made to simulate

30 the appearance of ornamental bands formed in the curtain top, said curtain top or extension being of such dimensions that when one of the rod engaging passageways other than the top one is used as the line of suspension for the curtain rod, the surplus fabric which is not utilized to extend 35 the body portion of the curtain is conserved in the form of an ornamental cuff or valance. The horizontal rows of eyelets are so arranged that at least one of the said rows is not in exact vertical alignment with the other row or rows of eyelets, but on the contrary is at least partially out of alignment with the other row or rows of eyelets, so that when the surplus fabric is folded 40 to bring corresponding eyelets in each row into cooperative registry there will be a partial overlapping of the eyelet openings, insufficient to obstruct the passage of the curtain rod but sufficient to lock the ornamental cuff or valance against slippage along the rod after the operator

45 has secured the curtain upon the rod in the preferred position. The rod engaging passageways are preferably spaced apart at a distance therebetween generally representing the amount of shrinkage in laundering, so that when the curtain 50 is re-hung after laundering it may be lockably

suspended from another rod engaging passageway constituting a new line of suspension so as to display the same length of curtain down hanging from the suspension rod as before.

In the drawings comprising three sheets of 5 seven figures numbered Figs. 1 to 7 inclusive, certain embodiments of the invention are set forth.

Fig. 1 is a plan view of one form of my improved adjustable curtain.

Fig. 2 is an elevation showing a portion of the 10 curtain of Fig. 1 in hung position to effect minimum length adjustment.

Fig. 3 is an elevation showing a portion of the curtain of Fig. 1 hung in another way to effect 15 minimum length adjustment while producing a different ornamental effect in the hung curtain.

Fig. 4 is a plan view of an alternative form of curtain embodying the improvements showing only the upper portion of said curtain, the lower portion thereof being broken away. 20

Fig. 5 is an elevation showing a portion of the curtain of Fig. 4 hung to effect intermediate length adjustment.

Fig. 6 is a plan view of the upper portion of 25 another modified form of curtain; and

Fig. 7 is a plan view of the upper portion of 30 still another modified form.

Like reference characters designate corresponding parts throughout the several figures of the drawings.

Referring to Figs. 1 to 3 the curtain 10 consists of a body portion 16 extending from the lower end of the curtain indicated by the hem 17 to the upper end of the body portion which terminates in the bottom rod engaging passageway formed by the lowermost horizontal row of eyelets 13. Eyelet passageway 13 in effect approximates the normal line of suspension for the curtain. Instead of terminating the curtain and finishing off its top edge immediately above 35 the rod engaging eyelet passageway 13, the curtain fabric is extended to provide a surplus of fabric constituting an extension or curtain top which may be constructed and utilized to adjust the length of the curtain when draped on a 40 longer window or to compensate for shrinkage of the curtain as in laundering, as hereafter described. Said surplus of fabric may be of any desired length but in general it has been found that very satisfactory results may be obtained 45 when three rod engaging passageways are fabricated, in which case the length of said surplus fabric is preferably such that the vertical distance from the finished edge of the upper extremity of the curtain to the bottom of the rod 50

engaging eyelet passageway 13 measures approximately nine (9) inches overall.

The curtain 10 may be woven on a lace making machine (such as a Nottingham lace curtain machine, Levers machine or the like), in which case the eyelet passageways formed by the rows of eyelets 11, 12, and 13 may form a part of the curtain pattern. In the closer weaves one may prefer to form the eyelets as indicated at 13 (Fig. 1), but in other curtains particularly those made from the coarser weaves, the eyelets are preferably woven in a horizontal band of fine mesh, forming part of the pattern, such as is indicated at 14 and 15 of Fig. 1. The lace bands 14 and 15 may form any preferred clothing effect to enhance the ornamental appearance of the curtain, but in the curtains 10 and 20 as illustrated in Figs. 1 and 4 a simple checker pattern clothing effect is shown. It should of course be understood that the clothing effect shown at 14 and 15 might also be repeated for the row of eyelets 13 and that the simple net indicated in the body portion 16 might if preferred be replaced by a more elaborate weave.

It should also be understood that a rod engaging hemmed passageway may be substituted for the rod engaging eyelet passageway 11, as shown at 113 of Fig. 41 of my application, Serial No. 741,614, filed August 27, 1934; or that the curtain top may be folded upon itself so as to effect partial registry of corresponding eyelets 11 and 12, which it will be observed are not in perfect vertical alignment, (see Fig. 5 showing partial registry of eyelets 21 and 22 under similar conditions) and the hem defined by the formed fold may be secured in place by one or more lines of stitches passing through both plies of the fabric and traversing the curtain 10 horizontally from side edge to side edge thereof. This construction is more fully shown and described at Figs. 20, 21, and 22 of my co-pending application, Serial No. 741,614, filed August 27, 1934. It should of course be understood that if the curtain of Fig. 1 were provided with a hemmed passageway as last described, the overall length of the ready-to-hang curtain including the extension portion thereof would be reduced approximately three inches, but this could be overcome by extending the curtain top and forming a fourth rod engaging eyelet passageway in the surplus fabric, having the same spacing as rod engaging eyelet passageways 11, 12, and 13 (such as is shown in Fig. 20 of my co-pending application, Serial No. 741,614, filed August 27, 1934), so that after folding and hemming in the manner previously described the finished curtain including the body portion 16 and the surplus fabric top portion would be the same length as the curtain shown in Fig. 1.

It should be observed that corresponding eyelets formed in the rod engaging eyelet passageways 11 and 13 are vertically aligned, while the corresponding eyelets in the rod engaging passageway 12 are only partially aligned with the eyelets of rod engaging eyelet passageways 11 and 13. When the curtain is folded once (Fig. 5) to effect intermediate length adjustment, or once (Fig. 3), or twice (Fig. 2), to effect minimum length adjustment, the eyelets formed in the rod engaging eyelet passageway 12 will register with the corresponding eyelets formed in the rod engaging eyelet passageways 11 and/or 13 sufficiently to permit free passage of the curtain or suspension rod 19 through the several (two or more) sets of cooperatively registering eyelets formed in the several folded plies. The curtain may now be manipulated upon the rod 19 (or 27) until the desired width and degree of ornamentation is obtained. After the curtain is adjusted to the preferred degree of ornamentation, it is released and the fabric in the folded plies tends to resume its natural alignment, and in so doing and because of their partial disalignment, the corresponding eyelets in the eyelet passageways 12, 11 and/or 13 tend to grip or become tensioned upon the curtain or suspension rod 19 (Figs. 2 and 3) or 27 (Fig. 5), thereby locking the several plies of the formed fold against slippage on the rod to maintain the sinuous pleats in the formed fold in the desired selected position. The manner in which the cooperatively registering eyelets tend to become partially disaligned to lock the plies to the curtain or suspension rod will be better understood by reference to Figs. 2, 3, and 5 of the drawings.

It should be understood that the surplus fabric of the curtain of Fig. 1 may be folded twice to effect minimum length adjustment and threaded upon the rod as shown in Fig. 2 to form an ornamental cuff surmounting the hung curtain. The 25 curtain is reversible, and may be hung to give a straight wall effect in front, with the cuff in rear, as shown in Fig. 2; or may be turned around to expose the cuff in the front of the curtain (all as more fully described in my co-pending application, Serial No. 741,614, filed August 27, 1934). It should also be understood that by weaving the eyelets of the rod engaging eyelet passageway 13 in an ornamental lace band, similar to the ornamental bands 14 and 15, the 35 curtain 10 will present substantially the same ornamental appearance on both sides when hung in the manner indicated in Fig. 2, instead of a plain effect on one side and an ornamental effect on the other which is produced when the 40 curtain 10 of Fig. 1 is hung as shown in Fig. 2.

The curtain 10 of Fig. 1 may likewise be hung to effect minimum length adjustment in the manner shown in Fig. 3 in which event a short valance like effect is produced.

Intermediate length adjustment is accomplished by folding the curtain once instead of twice and threading the cooperatively registered eyelets of the two plies upon the curtain or suspension rod 27 as shown in Fig. 5. In this case 50 the bottom row of eyelets formed in the bottom rod engaging eyelet passageway 23 (Fig. 4), or 13 (Fig. 1), will be included in and form a part of the body portion 26 of curtain 20 (Fig. 5), or of the body portion 16 of curtain 10 (Fig. 1). Similarly the rod 19 or 27 may be threaded through the rod engaging eyelet passageway formed by the row of eyelets 11 (Fig. 1) or 21 (Fig. 4), to effect maximum length adjustment as shown in Figs. 15 and 16 of my co-pending application, Serial No. 741,614, filed August 27, 1934.

In the alternative form of curtain 20 shown in Figs. 4 and 5, the eyelets formed in the middle and bottom rod engaging eyelet passageways 22 and 23 are in vertical alignment, while the eyelets formed in the uppermost rod engaging eyelet passageway 21 are only in partial vertical alignment with the corresponding eyelets of the rod engaging eyelet passageways 22 and 23. This 70 alternative construction will not however effect locking when the curtain is hung upon the rod 19 or 27 to produce a short valance like effect such as shown in Fig. 3. It should be understood however, that either curtain 10 or curtain 20 75

may be modified by folding the fabric between the two uppermost rod engaging eyelet passageways and then hemmed, and that when so folded and hemmed the curtain may be threaded through both rows of cooperatively registering (but partially disaligned) eyelets, and when so threaded locked upon the rod 19 or 27, as the case may be, without further folding. Such a construction will function the same as the curtain illustrated in Fig. 5 except that the false hem shown in the construction of Fig. 5 will have been made permanent.

In the curtain constructed as shown in Fig. 6 the eyelets forming the several rod engaging engaging eyelet passageways 31, 32, 33, and 34, are arranged in staggered relation relative to each other and at least partially disaligned to effect locking when the curtain is suspended upon the curtain or suspension rod 19 to produce a valance like effect such as is shown in Fig. 3. In this figure the curtain is provided with four rod engaging eyelet passageways but it should be understood that a curtain constructed in this manner may be provided with two or more of said rod engaging eyelet passageways as preferred. In this construction the outside eyelets of each rod engaging eyelet passageway may be aligned as indicated at 35 (Fig. 6). Instead of staggering all of the rows of eyelets (as shown in Fig. 6), alternate rows of eyelets 31—33 and 32—34, could be arranged in vertical alignment, and rows 31—33 could be partially disaligned relative to rows 32 and 34.

Fig. 7 shows a further modification having a plurality of rows of eyelets in vertical alignment, and a plurality of other rows of eyelets, positioned in staggered relation relative to the first plurality of rows of eyelets. The first and last eyelet in each row are preferably disposed (as at 46) relatively close to the side edges of the curtain 40. In the curtain 40 shown in Fig. 7, the rows of eyelets 41, 43, and 45, are spaced at substantially the same distance as in the curtains shown in Figs. 1 and 4, the rows of eyelets 42 and 44, being woven therebetween to provide for lengthening or shortening by one-half adjustments. It should be understood however that the spacings between each of the several rows of eyelets 41, 42, 43, 44, and 45 of curtain 40, may be the same as the spacings between the rows of eyelets 11, 12, and 30 of curtain 10 (Fig. 1), thereby effecting full length adjustments. It should also be understood that eyelets 42 and 44 may be arranged in partial disalignment relative to eyelets 41, 43, and 45 if preferred.

In some cases only certain eyelets 12 or 21 may be partially disaligned relative to the eyelets 11 and 13, or 22 and 23. For example the first, last, and one or more central eyelets of rod engaging eyelet passageways 12 and 21 may be disaligned, and the remaining eyelets aligned relative to eyelets 11 and 13 or 22 and 23. In some cases it is found that this arrangement sufficiently locks the curtain to the rod.

One or more rows of eyelets may be closed with cross threads as indicated at 47—47 (Fig. 7) which is merely illustrative. This arrangement is sometimes preferred where the curtains are to be hung with a certain row (or rows) of eyelets exposed, as for example, to effect minimum length adjustment as shown in Fig. 3 in which case the eyelets of rod engaging passageway 11 would be provided with the cross threads 47. When it is desired to use the closed eyelets, the cross threads are removed as by cutting with scissors,

and the rod engaging passageway is ready for use. The removal of the cross threads does not cause unravelling of the lockstitching, or other reinforcing threads, around the eyelet openings. The cross threads 47 may be used on any of the curtains shown in the several figures of the drawings, but they are particularly applicable to a curtain which allows for semi-adjustments such as the construction illustrated in Fig. 7.

It will be observed that the uppermost row of 10 eyelets is relatively close the extreme upper edge of the curtain, which edge is finished off with a selvage or by hemming, or in any other preferred manner, so that the edge band above the curtain rod will always stand erect even when 15 the curtain is suspended from the uppermost eyelet passageway only. The outermost vertical rows of eyelets are positioned relatively close to the side edges of the curtain, which edges are also finished off in any preferred manner as by a 20 selvage or by hemming. One or both side edges may be finished off with a relatively wide hem similar to bottom hem 17 (Fig. 1). By placing the outermost vertical rows of eyelets relatively 25 close to the side edges, better draping effects are obtained.

What is claimed is:

1. As an article of manufacture a ready-to-hang adjustable curtain having a body portion and a surplus fabric top portion merging with 30 the upper end of the body portion and in extension thereof, a plurality of horizontal rows of eyelets formed in said top portion constituting rod-engaging eyelet passageways for extending the body portion of the curtain to effect length 35 adjustment thereof, the spacing between said rows measuring generally the shrinkage in said curtain as in washing, corresponding eyelets in two of said rows being partially disaligned, the curtain being freely slideable upon a rod when 40 threaded thereon from either one of said rod-engaging eyelet passageways separately, the partially disaligned eyelets frictionally engaging the opposite walls of a rod to lock the curtain against free sliding movement relative thereto when the 45 said eyelet passageways are simultaneously threaded thereon, and a finished edge band at the upper extremity of the curtain.

2. As an article of manufacture a ready-to-hang adjustable curtain having a body portion and a surplus fabric top portion operable to extend the body portion to effect length adjustment thereof, the portion of said surplus fabric not so utilized being foldable to form an ornamental top defining either a cuff or a valance 55 dependent upon the surplus available for folding and the manner of folding the same, a horizontal row of eyelets positioned at the line of merger of said body and top portions and constituting a free passageway for a rod whereon the curtain 60 is suspendable to effect minimum length adjustment, a second horizontal row of eyelets formed in said surplus fabric in parallel spaced relation to said first row of eyelets constituting a second free passageway for a rod whereon the curtain 65 is separately suspendable to extend the body portion, the spacing between said rows of eyelets measuring generally the shrinkage in said curtain in washing, corresponding eyelets in the said rows being partially disaligned to effect frictional engagement with opposite faces of a rod to lock the curtain against free sliding movement relative thereto when the top portion is folded midway between said passageways and both rows of eyelets are simultaneously threaded 70 75

upon a curtain rod, and a finished edge band at the upper extremity of the top portion, the uppermost passageway being in close proximity to said edge band.

5   3. As an article of manufacture a ready-to-
hang adjustable curtain having a body portion
and a surplus fabric top portion merging with the
upper end of the body portion and in extension
thereof, three horizontal rows of eyelets formed
10   in said top portion constituting rod-engaging
passageways, said top portion being operable to
variously extend the body portion to effect length
adjustment thereof, the portion of said fabric
not so utilized being foldable to form an orna-
15   mental top defining either a cuff or a valance
dependent upon the surplus available for folding,
the manner of folding, and the number of pas-
sageways simultaneously threaded upon the rod,
one of said rows of eyelets being positioned at the
20   line of merger of said body and top portions, an-
other adjacent the upper extremity of the top
portion, and a third midway therebetween, the
spacing between two of said rows of eyelets meas-
uring generally the shrinkage in said curtain in
25   washing, the eyelets in one of said rows being
partially disaligned relative to the corresponding
eyelets in the remaining rows to effect frictional
engagement with opposite faces of a rod to lock
the curtain against free sliding movement rela-
30   tive thereto when the top portion is folded and
disaligned rows of eyelets are simultaneously
threaded upon a curtain rod.

4. As an article of manufacture a ready-to-hang adjustable curtain having a body portion and a surplus fabric top portion merging with the upper end of the body portion and in extension thereof, three horizontal rows of eyelets formed in said top portion constituting rod-engaging passageways, said top portion being operable to variously extend the body portion to effect length adjustment thereof, the portion of said fabric not so utilized being foldable to form an ornamental top defining either a cuff or a valance dependent upon the surplus available for folding, the manner of folding, and the number of passageways simultaneously threaded upon the rod, one of said rows of eyelets being positioned at the line of merger of said body and top portion.

tions, another adjacent the upper extremity of the top portion, and a third midway therebetween, the spacings between said rows of eyelets measuring generally the shrinkage in said curtain in washing, the eyelets in one of said rows being partially disaligned relative to the corresponding eyelets in the remaining rows to effect frictional engagement with opposite faces of a rod to lock the curtain against free sliding movement relative thereto when the top portion is 10 folded and disaligned rows of eyelets are simultaneously threaded upon a curtain rod, and a finished edge band at the upper extremity of the top portion, in close proximity to the uppermost row of eyelets. 15

5. As an article of manufacture, a ready-to-hang adjustable curtain having a body portion and a surplus fabric top portion merging with the upper end of the body portion and in extension thereof, three horizontal rows of eyelets formed in said top portion constituting rod-engaging passageways, said top portion being operable to variously extend the body portion to effect length adjustment thereof, the portion of said fabric not so utilized being foldable to form an ornamental top defining either a cuff or a valance dependent upon the surplus available for folding, the manner of folding, and the number of passageways simultaneously threaded upon the rod, one of said rows of eyelets being positioned at the line of merger of said body and top portions, another adjacent the upper extremity of the top portion, and a third midway therebetween, the spacings between said rows of eyelets measuring generally the shrinkage in said curtain in washing, the eyelets in one of said rows being partially disaligned relative to the corresponding eyelets in the remaining rows to effect frictional engagement with opposite faces of a rod to lock the curtain against free sliding movement relative thereto when the top portion is folded, and disaligned rows of eyelets are simultaneously threaded upon a curtain rod, and cross threads for closing the eyelets of one of said rows, said cross threads being removable as by cutting to permit threading of a rod therethrough.

HUGO GELLER.
